LOCOMOTIVE TENDER

Edwin Archer Turner, New York, N. Y., assignor
to The Standard Stoker Company, Incorporated,
a corporation of Delaware

Application November 12, 1930, Serial No. 495,041
Renewed August 17, 1933

24 Claims. (Cl. 105—234)

This invention has for an object to provide in a locomotive tender, a construction affording increased water capacity and a more rigid and durable structure reducing maintenance expense comprising a support member formed in the water section to support the fuel section and adapted to carry a separate fuel trough arranged with the support member and usual slope sheets of the fuel section to form a water tight partition between the fuel and water sections.

Other objects of the invention are the provision of a simple, durable and cheaply manufactured fuel trough and the provision of a rugged novel form of fuel section support member arranged to receive a fuel trough.

The invention consists in the form of the individual parts, and in the arrangement and combination of the parts as hereinafter fully described and defined in the appended claims.

20 On the drawings

Fig. 1 is a central longitudinal vertical section of a portion of a locomotive tender showing part of the stoking mechanism;

Fig. 2 is a section in a horizontal plane taken 25 on the line 2—2 of Fig. 1;

Fig. 3 is a transverse vertical section taken on the line 3—3 of Fig. 1;

Fig. 4 is an isometric view of the novel stoker fuel trough of the improved tender;

30 Fig. 5 is an isometric view of the novel support member of the improved tender; and

Fig. 6 is a fragmentary view similar to Fig. 1 illustrating a modified structure wherein a stoker drive mechanism compartment is formed integral with the rear portion of the support member.

The improved locomotive tender is indicated as a whole by the letter A and comprises the fuel section B and the water section C forming what 40 is usually termed a body portion above the tender base or frame D which in the construction shown affords a space 10 communicating through its apertured upper wall 11 with the water section C thereby providing increased water carrying capacity.

A support member indicated generally at E is disposed centrally and longitudinally of the tender forward portion of the water section C extending above the frame D forming a support 45 therefrom for the fuel section B and being arranged to carry a separate stoker fuel trough F as will presently appear. Preferably though not necessarily, the member E is separable from the tender frame and may be secured thereto in any 55 suitable manner such as by welding. The sup-

port member is substantially a four sided ring-like rectangular shaped casting comprising longitudinally extending sidewalls 12, 12a, apertured at 13, and rear and front transverse walls 14 and 15 respectively. The base plate 16 bounds centrally disposed opening 17 at the base of the member E communicating with the space 10 of the tender frame and the header 18 at the top portion of the support member carries a laterally inwardly directed ledge 19 and a laterally outwardly directed flange 20. The ledge 19 forms a seat 21 for the trough F, which seat in effect bounds an open top of the support member closed by the trough as will hereinafter be more specifically described.

The flange 20 is continuous about the longitudinal sides and rear wall of the support member and if preferred may be extended to form the usual slope sheets forming the fuel section B, but preferably, the flange 20 is relatively small 75 and is attached by welding or riveting to the lower marginal portions of separable side sheets 22, 22a and the rear sheet 23 constituting partition walls between the fuel and water sections. By this construction the member E supports the fuel section and its ledge 19 forms part of the floor thereof rearward of the usual tender deck 24. Transverse, perpendicular braces or ribs 25 join the header 18 and base plates 16 to strengthen the support member. 85

The fuel trough F is of novel form peculiarly adapted for use with the support member shown. In cross section as best shown in Figs. 3 and 4, the trough assumes a substantially V-shape having a laterally outwardly extending flange or ledge 30 at the upper end of its sidewalls, which flange or ledge extends longitudinally the length of the sidewall and is received by the seat 21 of the support member. The trough has an open rearward end being defined by the rearward marginal edges of its sidewalls and is so arranged with the support member that the rear wall 14 thereof constitutes a closure for the rearward end of the trough. 95

At its forward end the trough is provided with 100 a front transverse wall 31 which extends laterally beyond the sidewalls of the trough immediately forward of the front wall 15 of the support member to form a flange-like extension overlapping the V-shaped seat or opening in the 105 wall 15. By welding the marginal edges of the trough front wall 31, the marginal edges of the trough flanges or ledges 30 and the rearward marginal edges of its sidewalls to the adjacent parts of the support member a durable structure 110

and a watertight connection results. The trough front wall is apertured at 32 to receive the conveyor screw 33 mounted within the trough to advance fuel forwardly to any suitable form of fuel conduit, not shown, adapted to lead forwardly to the locomotive and at its rearward end being connected to the hollow spherical extension 34 formed integrally with the trough front wall and communicating with the opening 32 therein. A suitable crusher 35 also formed integrally with the trough front wall 31 extends rearwardly within the trough above the screw 33 and is arranged therewith to break down and crush lumps of fuel too large for firing.

15 Fuel from the fuel section B enters the trough through the opening 36 made by the shiftable slide plates 37. These plates together with the trough flanges 30, and the ledge 19 of the support member constitute a floor for the fuel section. The slide plates are received in the chamfered seat 38 of the trough and the forward plate may be shifted forwardly beneath the tender deck 24 and when in this position as shown in Fig. 1 the chamfered extension 39 provides a guiding 20 support for the plate.

Any suitable mechanism may be provided to drive the screw 33. There is shown for this purpose gearing comprising a pinion 40 and a gear 41 housed within the gear casing 42 detachably 30 mounted on the rear side of the rear wall 14 of the support member. An opening 43 in the rear wall 14 permits the use of the bearing 44 of the gear casing and allows the driven shaft 46 to extend into the trough for driving attachment in any suitable manner to the screw 33. The pinion shaft 47 may be connected to any desirable source of power but as shown it is coupled as at 48 to a drive shaft 49 extending longitudinally of the trough F to the forward 35 end of the tender, there being connected by the universal joint 50 to a prime mover or any other suitable power means not shown.

To protect the drive shaft 49 from the water it is enclosed within a housing 51 which preferably is formed integrally with a sidewall of the trough F extending lengthwise thereof and at its forward end opening through the wall 31 and at its rearward end opening through a lateral flange 52 flush with the rearward marginal 50 edges of the trough sidewalls and overlapping an opening 53 in the rearwall 14 of the support member, which opening communicates with the hollow housing 51 and is surrounded by the trough flange 52. By continuing the welding of the rearward marginal edges of the trough sidewalls about the flange 52, water is prevented from entering the gear casing 42 through the rear wall 14 of the support member.

The particular arrangement of the drive shaft 60 49 within the housing 51 will not be further described herein inasmuch as it is specifically described in my co-pending application Serial No. 447,451, filed April 26, 1930.

A watertight compartment G is formed within 65 the water section C forming with the rearward portion of the support member a housing for the gear casing 42. The compartment is closed on all sides except the bottom which is open communicating with a manhole 54 in the tender frame D permitting access to and replacement of the gear casing or its parts. This compartment may be formed by the sheets or plates 55 welded to an extension 57 of the support member backwall 14, or if preferred the sides 55a 70 of the compartment G may be formed integrally

with the support member as shown in Fig. 6 of the drawings. Also as shown in this figure the gear casing 42a may be formed integrally with the support member but the preferred construction is shown in Figs. 1 to 5.

The support member at its forward ends carries sidewall extensions 60 and 61 which form beneath the tender deck 24 a closure for the water section C and at the same time, provide an alcove 62 wherein the ball member 34 and the drive shaft joint 50 may be attached to any suitable form of stoker conduit. The extensions 60 and 61 are attached to the front wall 63 of the tender.

From the foregoing description it will be seen the invention affords an improved locomotive tender, more rugged and carrying more water than existing tenders, and in which the apertured support member E is arranged with a separate trough F and the slope sheets of the fuel section to form a watertight partition wall between the fuel and water sections.

I claim:

1. In a locomotive tender having a base, a body portion comprising fuel and water sections, 100 means for separating said sections including partition plates, a fuel trough and a supporting member having apertured sidewalls interposed between said base and said trough and being separable from each; said member, trough, and partition plates arranged to provide communicating water space underneath said plates and beneath the trough, the outer surface of said trough contacting the water in said water section, and a watertight compartment formed with said member within said water section for housing stoker 110 drive mechanism.

2. In a locomotive tender having a base, a body portion comprising fuel and water sections, 115 means for separating said sections including partition plates, a fuel trough and a supporting member having apertured sidewalls interposed between said base and said trough and being separable from each; said member, trough, and partition plates arranged to provide communicating water space underneath said plates and beneath the trough, the outer surface of said trough contacting the water in said water section, and a watertight compartment formed integral with 120 said supporting member at the rear thereof with- 125 in said water section for housing stoker drive mechanism.

3. In a locomotive tender having a base, a body portion comprising fuel and water sections, 130 means for separating said sections including partition plates, a fuel trough and a supporting member having apertured sidewalls interposed between said base and said trough and being separable from each; said member, trough, and partition plates arranged to provide communicating water space underneath said plates and beneath said trough, the outer surface of said trough contacting the water in said water section, a watertight compartment formed integral with said member within said water section for housing 135 stoker drive mechanism, and said base having an opening therethrough beneath said compartment permitting access thereto.

4. In a locomotive tender having a base, a body portion comprising fuel and water sections including partition plates between said sections, 145 a support member extending above said base and carrying a flange for watertight attachment to the lower marginal edges of said partition plates, the longitudinally extending sidewalls of said 150

- member being apertured to permit the passage of water therethrough, and a fuel trough separate from said support member mounted thereon and secured therewith to form a watertight connection, the outer surface of said trough contacting the water in said water section. 5. In a locomotive tender having a base, a body portion comprising fuel and water sections including partition plates between said sections, a support member extending above said base and carrying a flange for watertight attachment to the lower marginal edges of said partition plates, the longitudinally extending sidewalls of said member being apertured to permit the passage of water therethrough, and a fuel trough separate from said support member mounted thereon and welded thereto forming with said member and partition plates a watertight partition wall separating the fuel and water sections, the outer surface of said trough contacting the water in said water section. 6. In a locomotive tender having a base, a body portion comprising fuel and water sections, a four-sided ring-like integral support member in the water section extending above said base forming a support therefrom for said fuel section and having its longitudinally extending sidewalls apertured below said fuel section and at its upper portion carrying a seat bounding an opening through the top of said member, and a fuel trough separate from said member mounted on said seat thereof forming a watertight section therewith, the outer surface of said trough contacting the water in said water section. 7. In a locomotive tender having a base, a body portion comprising fuel and water sections, a four-sided ring-like support member in the water section extending above said base forming a support therefrom for said fuel section, a seat in said support member bounding an opening through the top thereof, a fuel trough having an open rearward end mounted on said seat, said open rearward end being defined by the rearward marginal edges of the sidewalls of the trough, which rearward marginal edges butt against a transverse rear wall of said support member, said rearward marginal edges being welded to said support back-wall and the other marginal edges of said trough being welded in said seat of the support member, and the longitudinally extending sidewalls of said member apertured to permit circulation of water beneath said trough, the outer surface of said trough contacting the water in said water section. 8. In a locomotive tender having a base, a body portion comprising fuel and water sections, a four-sided ring-like support member in the water section extending above said base forming a support therefrom for said fuel section, said member having longitudinally extending apertured sidewalls, a transverse rearwall on its rearward side carrying a gear casing, and a transverse front wall forming with the front tender wall a closure for the water section beneath the fuel section, a seat in said support member bounding an open top thereof, a fuel trough mounted in said seat and having at its forward end a laterally extending flange disposed closely adjacent the outer surface of the front wall of said member and overlapping the portion of said seat therein and said trough having an open rearward end being defined by the rearward marginal edges of the trough sidewalls, which edges butt against the forward side of the rearwall of said member, and the marginal edges of said trough being welded to said support member, the outer surface of said trough contacting the water in said water section. 9. In a locomotive tender having a base, a body portion comprising fuel and water sections, a four-sided ring-like support member in the water section extending above said base forming a support therefrom for said fuel section, said member having longitudinally extending apertured sidewalls, a transverse rearwall and a transverse front wall forming with the front tender wall a closure for the water section beneath the fuel section, a seat in said support member bounding an open top thereof, a fuel trough mounted in said seat and having at its forward end a laterally extending flange disposed closely adjacent the outer surface of the front wall of said member and overlapping the portion of said seat therein and said trough having an open rearward end being defined by the rearward marginal edges of the trough sidewalls, which edges butt against the forward side of the rearwall of said member, a drive shaft casing extending longitudinally of said trough at one side thereof between the rear and front walls of said member and opening through each wall, said rearwall of the support member having an opening therethrough communicating with said trough, a gear casing mounted on the rear side of said rear wall including gearing comprising a shaft extending through the opening in said rear wall communicating with said trough and a shaft extending through said rear wall into said casing, and the rearward marginal edges of said trough and casing welded to the rear wall of said support member forming a watertight connection therewith preventing passage of water into the gear casing and the remaining marginal edges of said trough and casing welded to said seat in said member forming a watertight connection therewith between the fuel and water sections, the outer surface of said trough contacting the water in said water section. 10. In a locomotive tender having a base, a body portion comprising fuel and water sections, a four-sided ring-like support member in the water section extending above said base forming a support therefrom for said fuel section, said member having longitudinally extending apertured sidewalls, a transverse rear wall and a transverse front wall forming with the front tender wall a closure for the water section beneath the fuel section, a seat in said support member bounding an open top thereof, a fuel trough mounted in said seat and having at its forward end a laterally extending flange disposed closely adjacent the outer surface of the front wall of said member and overlapping the portion of said seat therein and said trough having an open rearward end being defined by the rearward marginal edges of the trough sidewalls, which edges butt against the forward side of the rearwall of said member, a drive shaft casing formed integral with said trough extending longitudinally at one side thereof and at its forward end opening through said laterally extending flange of the trough and at its rearward end terminating in the same vertical plane as the rear marginal edges of said trough, said casing at its rearward end bounded by a flange extending laterally from the trough, said rearwall of the support member having an opening therethrough communicating with said trough and an opening communicating with said drive shaft casing, a gear housing mounted on the rear side of said rear wall enclosing gearing comprising shafts extending through the aforesaid openings in said rearwall communicating with said trough and said casing, and the rearward marginal edges of said casing, and the rearward marginal edges of

- said trough and its rearward laterally extending flange bounding said casing being welded to the forward side of the rearwall of said support member forming a watertight connection therewith preventing passage of water into the gear housing and the remaining marginal edges of said trough welded to said seat of the support member forming a watertight connection therewith between the fuel and water sections, the outer surface of said trough contacting the water in said water section. 80
11. A support member for a locomotive tender fuel trough and fuel and water section partition plates comprising a four sided rectangular shaped ring-like member with an open top and an open bottom formed by longitudinally extending upwardly apertured sidewalls and transverse upright end walls, said walls circumscribing a continuous opening between said open top and said open bottom. 85
12. A support member for a locomotive tender fuel trough and fuel and water section partition plates comprising a four sided rectangular shaped ring-like member with an open top and an open bottom formed by longitudinally extending upwardly apertured sidewalls and transverse upright end walls, said walls circumscribing a continuous opening between said open top and said open bottom, and said sidewalls at their top portions having formed therewith a laterally and inwardly extending ledge arranged to receive a tender fuel trough and a laterally and outwardly extending flange arranged for attachment to tender partition plates. 90
13. A support member for a locomotive tender fuel trough and fuel and water section partition plates comprising a four sided rectangular shaped ring-like member with an open top and an open bottom formed by longitudinally extending upwardly apertured sidewalls and transverse upright end walls, said walls circumscribing a continuous opening between said open top and said open bottom, and said sidewalls at their top portions having formed therewith a laterally and inwardly extending ledge arranged to receive a tender fuel trough and a laterally and outwardly extending flange arranged for attachment to tender partition plates, and the rearward endwall at its top portion having a rearwardly extending flange forming a transverse continuation of said sidewall flanges. 105
14. A support member for a locomotive tender fuel trough and fuel and water section partition plates comprising a four sided rectangular shaped ring-like member with an open top and an open bottom formed by longitudinally extending upwardly apertured sidewalls and transverse upright end walls, said walls circumscribing a continuous opening between said open top and said open bottom, and said sidewalls at their top portions having a ledge formed therewith arranged to receive a separate tender fuel trough. 110
15. As a new article of manufacture, a one piece integral casting comprising a locomotive tender fuel trough having an open rearward end, said open end being defined by the rearward marginal edges of the sidewalls of said trough, a hollow spherical ball member forward of said trough and communicating therewith, a drive shaft casing extending along one side of the trough, and a fuel crusher formed within the trough. 115
16. As a new article of manufacture, a fuel trough having an open rearward end, said open end being defined by the rearward marginal edges of the sidewalls of said trough, an apertured transversely extending front wall, said front wall projecting laterally at each side of the trough and at its forward end opening through the lateral projection of said front wall. 120
17. As a new article of manufacture, a one piece integral casting comprising a locomotive tender fuel trough having an open rearward end, said open end being defined by the rearward marginal edges of the sidewalls of said trough, a flange projecting laterally from the upper marginal edge of each sidewall of said trough, said flanges having adjacent beveled edges, a transversely extending front wall having an opening therethrough, and a hollow spherical ball member extending forwardly from said front wall and communicating with the opening therein. 125
18. As a new article of manufacture, a cast metal fuel trough V-shaped in cross section and having an open rearward end, said open end being defined by the rearward marginal edges of the sidewalls of said trough, a flange projecting laterally from the upper marginal edge of each sidewall of said trough, said flanges having adjacent beveled edges, and an apertured transversely extending front wall, said front wall projecting laterally at each side of the trough to form a connecting flange. 130
19. As a new article of manufacture, a cast metal fuel trough V-shaped in cross section and having an open rearward end, said open end being defined by the rearward marginal edges of the sidewalls of said trough, an apertured transversely extending front wall, said front wall projecting laterally at each side of the trough, and a flange projecting laterally from the upper marginal edge of each side wall of said trough, said flanges having adjacent beveled edges, each flange extending substantially the length of the trough and at its forward end uniting with said front wall. 135
20. As a new article of manufacture, a cast metal fuel trough V-shaped in cross section and having an open rearward end, said open end being defined by the rearward marginal edges of the sidewalls of said trough, an apertured transversely extending front wall, said front wall projecting laterally at each side of the trough, and a hollow drive shaft casing extending along one side of said trough and at its forward end opening through the lateral projection of said front wall. 140
21. As a new article of manufacture, a cast metal fuel trough V-shaped in cross section and having an open rearward end, said open end being defined by the rearward marginal edges of the sidewalls of said trough, an apertured transversely extending front wall, said front wall projecting laterally at each side of the trough, a hollow drive shaft casing extending along one side of said trough and at its forward end opening through the lateral projection of said front wall, and a hollow spherical ball member extending forwardly from said front wall and communicating with an aperture therein. 145
22. As a new article of manufacture, a cast metal fuel trough V-shaped in cross section and having an open rearward end, said open end being defined by the rearward marginal edges of the sidewalls of said trough, an apertured transversely extending front wall, said front wall projecting laterally at each side of the trough, a hollow drive shaft casing extending along one side of said trough and at its forward end open- 150

ing through the lateral projection of said front wall, a hollow spherical ball member extending forwardly from said front wall and communicating with an aperture therein, and a fuel crusher formed within said trough.

23. As a new article of manufacture a stoker trough housing comprising a four sided rectangular shaped ring-like member with an open top and an open bottom formed by longitudinal extending upstanding apertured sidewalls, transverse upright end walls, said sidewalls at their top portions having formed therewith a laterally and inwardly extending ledge arranged to receive a tender fuel trough and a laterally and outwardly extending flange arranged for attachment to tender partition plates, said sidewalls at their bottom having formed therewith a base plate, and upstanding ribs extending transversely of said

sidewalls joining said ledge and said flange with said base plate.

24. In a locomotive tender having a base, a body portion comprising fuel and water sections, means for separating said sections including partition plates, a fuel trough and a supporting member having apertured sidewalls interposed between said base and said trough and being separable from each, said member, trough, and partition plates arranged to provide communicating water space underneath said plates and beneath the trough, the outer surface of said trough contacting the water in said water section, and the upper end portion of said member being constructed for attachment to said partition plates for supporting the same and being arranged to receive and support said trough.
